APPARATUS FOR WINDING WIRE ON AN
ANNULAR BODY

Hendrik Jan van den Berge and Cornelis Gerardus Schrameyer, Eindhoven, Netherlands, assignors to Hartford National Bank and Trust Company, Hartford, Conn., as trustee

Application February 6, 1947, Serial No. 726,884
In the Netherlands May 16, 1944

Section 1, Public Law 690, August 8, 1946
Patent expires May 16, 1964

5 Claims. (Cl. 242—4)

1

Well-known winding apparatus for winding wire on an annular body are constituted by an annular chute driven in a circular path and serving as the wire stock. Part of this annular chute is removable to permit of the chute being introduced into the space enclosed by the annular body. After introduction of this chute the removed portion is again inserted and the length of wire required for the arrangement of a single winding on the annular body is then wound on the annular chute from an independent supply reel. The end of this wire is secured to a point intended for this purpose of the annular body to be wound. By rotation of this annular chute and the body to be wound about their respective axes, the winding is placed in position. When the body to be wound is ready the supply of wire on the annular chute should be completely used in order to permit of the chute being opened and the wound body being removed. For each winding the required length of wire must consequently be wound again on the annular chute and this appreciably prolongs the duration of the manufacture in the mass-production of wound annular bodies such as Pupin coils, annular bodies, wire-wound control resistances or the like.

According to the invention, the manufacture of such windings is considerably simplified by the fact that the stock of wire is constituted by a reel adapted to rotate about a spindle fastened to a ring-segment shaped carrier driven in a circular path, this reel being provided with means of constantly keeping the wire taut between this reel and the body to be wound.

Winding an annular stock beforehand with a measured length of wire can thus be omitted, as, without difficulty, the stock reel may comprise a quantity of wire for a plurality of bodies to be wound, since, when an annular body is wound, the wire can be broken off and the wound body can be removed through the opening between the ends of the ring segment.

The next body to be wound is inserted, the beginning of the wire is again secured to a point intended for this purpose and the winding machine is again put into operation. The gap between the ends of the ring segment may, if desired, be closed by the insertion of a fitting second segment. This is however not at all essential, as the uninterrupted drive and guide-way of a ring segment is also possible, if use is made of at least two driving members which are spaced apart a greater distance than the gap between the ends of the segment. When the stock reel is empty, it need not be rewound on a machine, but a full reel

2

may be substituted. This permits of providing windings on annular bodies considerably more rapidly than in known apparatus of the kind comprising the closed annular stock.

In addition, with the winding apparatus according to the invention the wire to be wound need not fulfill such high requirements, because the mass of the feed reel reciprocating during the winding operation is appreciably smaller than the mass of an annular chute. This renders the winding apparatus according to the invention suitable for winding wires of low thickness, for example of 100 microns and less.

As a matter of course, the diameter of the feed reel mounted on the carrier is limited by the shape of the inner profile of the annular body to be wound. Thin wires, such, for example, as resistance wires for winding the annular resistance bodies can, however, be arranged, without difficulty, on reels having a diameter of 10 millimeters and less.

During the winding of the wire about the annular body the supply reel is constantly rotating. During the half-revolution of the carrier during which the supply reel is moving away from the body to be wound, a length of wire is uncoiled and during the next half-revolution a slightly smaller length of wire must again be wound up, the supply reel approaching the body to be wound. In order that the wire to be wound may be applied to the annular body at any time so as to be taut the aforesaid means are provided for keeping taut the length of wire between the reel and the body to be wound. These means may comprise a spring and a friction clutch which are arranged between the reel and the carrier of this reel. The friction clutch is constructed in such manner that the greatest turning effect to be transmitted by this clutch is lower than the maximum turning effect the spring is capable of exerting. During the first half-revolution of the carrier, the wire being consequently wound off, the spring is put under tension. At the end of this half-revolution the friction clutch slips through such an angle that the wire length required for one winding is wound off the reel. During the second half-revolution the wire is rewound by the stretched spring. From a structural viewpoint these means are very simple and particular control members may be omitted. It might be looked upon as a drawback that for putting the friction clutch into operation a rather abrupt pull at the winding wire is required.

The aforesaid drawback can be avoided by coupling the supply reel with the spindle of an elec-

tric motor whose direction of rotation is such as to constantly tend to rewind the wire on the reel. In this case, during the first half-revolution of the carrier the armature of the electric motor is turned against the action of the electric field and the electric current. Such a coupling may operate smoothly, but has the disadvantage of requiring particular members for the supply of current to the electric motor seated on the rotary carrier.

According to one embodiment of the invention the aforesaid disadvantages can be avoided in that part of the supply reel contacts at any time with a stretched rope which is stationary relatively to the carrier of this reel and concentric to the circular part of the carrier. By the supply reel travelling along the circular path traversed by the carrier, this reel is driven, so to speak, by the rope moving relatively past it and that in such manner that this movement results in the wire being always wound up. During the first half-revolution of the carrier the rope slips over the periphery of the reel moving in the opposite direction, the winding wire thus remaining constantly under tension.

The friction between this rope and the reel is very even throughout the path of the reel, so that the occurrence of shocks in the winding wire is avoided. The magnitude of this friction is adjustable by varying the tensile stress in the rope. In addition, this flex takes very little room, so that the space available for the supply reel in the inner profile of the body to be wound is practically not restricted.

In order that the invention may be clearly understood and readily carried into effect, it will now be set out more fully with reference to the accompanying drawing, in which one form of construction is shown by way of example.

Fig. 1 is a front view of a winding machine according to the invention.

Figs. 2 and 3 are sectional views of several parts of this winding machine.

The winding machine consists of a vertically arranged base plate 10, to which a circular plate 14 is fastened by means of a plurality of bolts 13. The circumference of this plate is profiled in such manner that inter alia between this plate and the base plate 10 a circular groove having a rectangular cross-sectional profile 15 is formed. A flange of a ring segment 16 is adapted to move in this groove. This ring segment 16 serves as a movable carrier for the supply reel 17 which is provided with the winding wire. This supply reel is seated on a spindle 18 secured to the carrier 16.

The base plate 10 and the circular plate 14 fastened to it comprise a rectangular hole 11 which extends inwardly from the periphery of the base plate and whose size is sufficiently large for accommodating the biggest body to be wound. The ring segment extends through an angle exceeding 180°, so that it is held in the groove 15 rotatably but nevertheless unremovably. The angle is smaller than 360°, so that between the two ends 19 of this segment an opening of the same order of magnitude as the height of the aforesaid recess 11 is left. This opening serves for the insertion into the ring segment 16 of an annular body 12 that may be entirely closed, in such manner that during the movement of the segment about the centre the space enclosed by the annular body 12 is crossed.

The said ring segment 16 is driven by means of two gear-wheels 21 and 22 coupled with one another which engage a toothed rim 20 provided on the external periphery of the ring segment.

The two gear-wheels 21 and 22 are spaced apart a greater distance than the shortest spacing between the end surfaces 19 of the segment, so as to permit one of the gear-wheels 21 and 22 always engaging the ring segment and ensuring the drive of this segment.

The ring segment 16 supports not only the supply reel 17 already mentioned but also a guide roller 23 for the winding wire, said roller being secured to a spindle 24 which is also fixed to the segment 16. When the ring segment is caused to rotate by means of the two gear-wheels 21 and 22, the stock reel 17 as well as the guide roller 23 will move periodically through the space enclosed by the annular body 12 to be wound and their path will be closed again outside this body. The winding wire 25 whose end is secured beforehand to a point of the body 12, will, owing to this movement in a plane through the cylinder axis of the annular body 12, be wound about the annular body 12. The ring 16 is supported, however, upon an arm 26 adapted to rotate about an axis 27 parallel to or coinciding with the axis of the annular body 12. During the winding operation this arm is constantly rotated by means of a gear-wheel 28 and a toothed rack 29 engaging it, so that as a result the wire 25 is wound helically about the body 12.

During the rotary movement of the ring segment 16 the distance between the wound section of the body 12 and the guide roller 23 or the supply reel 17 respectively, is periodically increased and decreased. Owing to this relative movement of the stock reel or the guide roller, respectively, and the body to be wound a length of winding wire must periodically be uncoiled and then a length, if slightly smaller, must be rewound. For this purpose a separate drive of the stock reel 17 is required and this drive must be active in any case while the wire is being wound on the reel. For the sake of simplicity a rewinding device is chosen which constantly tends to cause the stock reel to be rewound, but which by the intermediary of a slip coupling also allows of the reel being uncoiled. The means for accomplishing this end comprises a rope 31 arranged in an annular groove 30 of plate 14. This rope is secured at one end to a fixed point 32 of the base plate 10 and at the other end is subjected to the tensile stress of a retracting spring 33 variable in length. This rope is over a substantial part of its length concentrically arranged to the ring segment 16; in addition it is led through a groove 34 of the stock reel 17 specially provided for this purpose and through a groove 35 of the guide roller 23. During the movement of the ring segment 16 and the stock reel 17 and guide roller 23 fastened to it, this rope which is stationary relatively to the moving ring will cause the stock reel and the guide roller to rotate in a direction opposite to the one in which the ring segment moves. The winding wire 25 is wound on the stock reel 17 in such manner that during the movement of the ring segment 16 this wire is wound on the stock reel in the direction indicated. During a half-revolution, when wire is to be uncoiled, the rope 31 slips over the grooves 34 and 35 of the stock reel and guide roller respectively; as soon, however, as the wire has reached the maximum length and the stock reel moves again in the direction of the body 12 the wire will be rewound at once, without any slack being produced in the wire.

The force with which the wire must be wound up varies with the thickness and the rigidity of the material of the wire 25. This force is vari-

able by changing the tension of the spring 33, so that the winding machine can be rendered suitable for differing forms of wire. The part of the rope which is not located in the grooves 34 and 35 of the two rollers, lies in the circular groove 30 provided in the periphery of the circular plate 14. In order to prevent an interruption of the drive the rope 31 is located in the groove 30 for more than a complete turn. Similarly to the grooves 34 and 35, groove 30 has therefore a width which is slightly greater than double the thickness of the rope 31. By soaking this rope with oil, the friction with the rollers 17 and 23 can be rendered very even, so that this winding machine permits the use of wire having a thickness of 20 microns.

The stock reel 17 has a given wire-wound width, so that the point from which the wire leaves this reel varies as the reel is uncoiled. Such a shifting of the wire would involve that the point at which this wire reaches the section to be wound is not a fixed one. For a correct guiding of the wire, provision is therefore made of the guide roller 23 whose circumference is provided with a V-like profile. The uncoiling wire always remains in the apex of the V, no matter from what point of the stock reel the wire comes. This guide roller 23 is also driven from the rope 31 in order that the acceleration forces which inevitably occur during the change of the direction of rotation of this roller when changing from the periodical winding to the periodical uncoiling of the wire may not be detrimental to this wire. It is also possible to have this guide roller 23 acted upon by a separate carrier, for example, by a carrier which concentrically to the carrier shown is located in or outside the latter.

In this case the drive of this roller may either be omitted completely or be effected by separate means in an appropriate manner.

What we claim is:

1. In a wire winding machine of the type including a wire supply reel, an annular body to be wound, and rotating carrier means for moving said reel in a circular path through said annular body, in combination a wire tensioning means comprising an elongate flexible member stationary with respect to said carrier and arranged substantially concentric with the same, part of said member being arranged in contact with the wire supply reel in a position enabling it to rotate said reel around its axis in a direction opposite to the direction of its travel on said carrier, for taking up slack wire during the period when said reel moves toward said annular body.

2. In a wire winding machine of the type including a wire supply reel, an annular body to be wound, rotating carrier means for moving said reel in a circular path through said annular body, and a stationary support for said carrier, in combination a wire tensioning means comprising a rope stationary with respect to said carrier, a circular groove on said carrier support adapted for receiving said rope in substantially concentric arrangement with said carrier, one end of said rope being attached to a fixed point on the frame of said machine, the other end of said rope being resiliently held on said frame, and an intermediate portion of said rope being arranged in contact with the wire supply reel in a position enabling it to rotate said reel around its axis in a direction opposite to the direction of its travel on said carrier, for taking up slack wire during the period when the reel moves toward said annular body.

3. In a wire winding machine of the type including a wire supply reel, a guide reel associated therewith, an annular body to be wound, notching carrier means for moving said reels in a circular path through said annular body and a stationary support for said carrier, in combination a wire tensioning means comprising a rope stationary with respect to said carrier, a circular groove on said carrier support adapted for receiving said rope in substantially concentric arrangement with said carrier, one end of said rope being attached to a fixed point of the frame of said machine, the other end of said rope being resiliently held on said frame, and an intermediate portion of said rope being arranged in contact with the wire supply reel and with the guide reel in a position enabling it to rotate said reels around their respective axis in a direction opposite to the direction of their travel on said carrier, for taking up slack wire during the period when the reels move toward said annular body.

4. In a wire winding machine of the type including a wire supply reel, a guide reel associated therewith, an annular body to be wound, rotating carrier means for moving said reels in a circular path through said annular body, and a stationary support for said carrier, in combination a wire tensioning means comprising a rope stationary with respect to said carrier, adjustable spring means mounted on the frame of the machine for attaching thereto one end of said rope, the other end thereof being secured to a fixed point on said frame, a circular groove on said carrier support adapted for receiving a portion of said rope in substantially concentric arrangement with said carrier, a circular groove each in said wire supply reel and said guide reel for receiving other portions of the rope thereby enabling it to rotate the said reels around their respective axis in a direction opposite to the direction of their travel on said carrier, for taking up slack wire during the period when the reels move toward said annular body.

5. In a wire winding machine of the type including a wire supply reel, an annular body to be wound, rotating carrier means for moving said reel in a circular path through said annular body, in combination a wire tensioning means comprising an elongate flexible member stationary with respect to said carrier, adjustable spring means mounted to the frame of the machine for attaching thereto one end of said flexible member, the other end thereof being attached to a fixed point of said frame, part of said flexible member being arranged substantially concentric with said carrier means, another part of said member being arranged in contact with the wire supply reel in a position enabling said member to rotate the reel around its axis in a direction opposite to its travel on said carrier for taking up slack wire during the period when the reel moves toward said annular body.
